HEAT TREATING APPARATUS

Frank McGuire, Jr., Bogota, N. J., assignor to
The Linde Air Products Company, a corpora-
tion of Ohio

Application June 15, 1940, Serial No. 340,645

12 Claims. (Cl. 266—5)

This invention relates to heat treating apparatus useful for locally hardening surface portions of metal bodies, such as gear teeth, and more particularly to apparatus which includes a device for accurately positioning a pair of blowpipe heads in operative relation with respect to a gear tooth.

A particularly effective manner of locally hardening a surface of a metal body, such as a side or wearing surface of a gear tooth, consists in applying high temperature heating flames followed by cooling jets against successive portions of the surface. It is particularly desirable to harden both sides or wearing surfaces of a gear tooth simultaneously, to avoid the possibility of reheating a previously hardened surface, and also to obviate the possibility of causing warpage due to local expansion and contraction of one side only of the tooth. To secure the maximum benefits from hardening both sides of the tooth simultaneously, it is desirable to position the heating flames, and also the cooling jets, exactly opposite each other on opposite sides of the tooth. It is also desirable that the flames on each side of the tooth impinge upon the tooth surface at the same angle; and that the blowpipe heads, from which the heating flames and cooling jets normally are discharged, be spaced the same distance from each tooth surface. On the one hand, it is necessary that the blowpipe heads be positioned with extreme accuracy, but, on the other hand, too much time should not be taken to position the heads, because the apparatus lies idle during positioning and the cost of treatment is thereby increased.

In accordance with previous practices, a drill is inserted in each blowpipe head, in one of the outlets from which the heating flames are discharged—in order to adjust the distance between each head from the tooth, to determine the points at which the flames will impinge upon the tooth surface, and to determine the angle of impingement of the heating flames and cooling jets. Insertion and reinsertion of a drill in a heating flame outlet tends to mar the outlet and thereby lower the efficiency of the head, since an irregularity in an outlet tends to cause the heating flame discharged from that outlet to burn improperly, thus tending to produce backfires and flashbacks. Moreover, such a method of positioning the heads requires considerable time, and only a highly skilled operator can position the heads with the highest degree of accuracy. Also, the correct set-up for a particular type and size of tooth cannot be duplicated at some later time

without repeating the entire setting-up operation.

Among the objects of this invention are to provide apparatus for heat treating gear teeth which include a novel positioning device by which a pair of blowpipe heads may easily be adjusted to any predetermined position relatively to a gear tooth; to provide such a positioning device by which the heads may be assembled accurately in position at a work bench or any other convenient place, and the heads then attached to the remainder of the apparatus with assurance that the heads will be in accurate position relatively to the gear tooth to be treated; to provide such a positioning device which will hold the heads accurately in position during treatment of a gear tooth; to provide heat treating apparatus in which the pressure of quenching liquid is maintained constant; to provide such apparatus by which a pair of blowpipe heads may be supplied with a combustible mixture of gases from a single blowpipe and also may be supplied with a quenching medium from a single source thereof; and to provide apparatus for heat treating gear teeth by which a pair of blowpipe heads may be supported for universal movement in a plane. Other objects and novel features of this invention will become apparent from the following description and accompanying drawings, in which:

Fig. 1 is an end elevation of apparatus constructed in accordance with this invention, in which a pair of blowpipe heads are held by a novel positioning device in inoperative relation with respect to a tooth of a gear;

Fig. 2 is a perspective view, looking downwardly at a small angle, illustrating more particularly the positioning device and attached blowpipe heads of Fig. 1;

Fig. 3 is a rear elevation of the positioning device and blowpipe heads of Fig. 1;

Fig. 4 is a rear elevation of an alternative positioning device and a pair of blowpipe heads in operative position with respect to a gear tooth;

Fig. 5 is a top view of the positioning device and blowpipe heads of Fig. 4;

Fig. 6 is a rear elevation of the positioning device of Figs. 4 and 5 and a pair of blowpipe heads of a slightly different type in operative relation with respect to a gear tooth;

Fig. 7 is a fragmentary front elevation of the positioning device of Figs. 4—6;

Fig. 8 is a side elevation of apparatus constructed in accordance with this invention for supporting a pair of blowpipe heads for universal movement in a plane, and by which the blowpipe

heads may be supplied with a combustible mixture of gases from a single blowpipe and a cooling medium from a single source;

Fig. 19 is an end elevation, partly broken away, on an enlarged scale, of the blowpipe heads of Fig. 1 and a modified form of positioning device through which a cooling medium may be circulated;

Fig. 20 is a transverse sectional view taken along line 20—20 of Fig. 19;

Fig. 21 is a side view of the right hand blowpipe head of Fig. 6; and

Figs. 22 and 23 are longitudinal sectional views taken along lines 22—22 and 23—23, respectively, of Fig. 21.

The apparatus illustrated in Figs. 1-3 comprises, in general, a pair of blowpipes B and B' mounted on a support S, in turn mounted on a carriage C; a pair of heating heads H and H' clamped in a positioning device D and supplied with a combustible mixture of gases by blowpipes B and B'; and a quenching medium supply Q, which supplies heads H and H' with a quenching medium at substantially constant pressure. The heads H and H', as in Fig. 1, are in operative position for hardening oppositely disposed wearing surfaces of a tooth T of a gear G. Gear G of Figs. 1 and 2 has relatively small teeth, and there is thus insufficient room between two teeth for a head to enter completely. Heads H and H' are therefore so constructed that the heating flames and cooling jets are discharged against the tooth surfaces from the lower end of each head, rather than from the side of each head, which is possible when larger gear teeth are being treated and the heads can be positioned between the teeth, as in Fig. 6. For moving the heads along the tooth, or downwardly in Fig. 2, carriage C runs along a flanged track T, which is preferably positioned with the flanges parallel to the center line of the tooth being treated, so that the heads H and H' will traverse a path which is parallel to the sides of the tooth. Carriage C is constructed as disclosed in U. S. Patent No. 2,183,605, being a four wheeled self-propelled mechanism, but it will be understood that any other suitable traversing mechanism or carriage may be utilized.

Carriage C is provided with a slide 4 adjustable laterally by a hand wheel 5, while a vertical guide 6 is secured to the end of slide 4. A slide 7, which fits into vertical grooves in guide 6, is moved upwardly or downwardly by a screw 8 which may be turned by a hand wheel 9. A horizontal arm 10 of support S is attached to

slide 7 by a bolt 11, and arm 10 is slotted, so that a slotted vertical arm 12 is movable along arm 10, and may be secured thereto in any desired position by a bolt 13 which extends through

the slot in arm 10. A slide 14, to which blowpipe B' is secured by a clamp 15, is similarly adjustable along horizontal arm 10. A slide 16, to which blowpipe B is secured by a clamp 17, is movable vertically along arm 12. Slides 14 and

10 16 respectively may be secured in any desired vertical or horizontal position by bolts similar to bolt 13 and which extend through the slots in arms 10 and 12, respectively. The support S, through slides 14 and 16 and clamps 15 and 17, 15 permit vertical and radial adjustment of blowpipe B and horizontal and radial adjustment of blowpipe B'.

The support S herein illustrated is similar to that disclosed in the application of Roger O. Day, Serial No. 169,373, filed October 16, 1937, now U. S. Patent No. 2,224,006 but other supports may be used, such as that disclosed in the application of Roger B. White, Serial No. 169,379, filed October 16, 1937, now U. S. Patent No. 2,224,007.

Blowpipes B and B' are each supplied with a combustion supporting gas, such as oxygen, and a combustible gas, such as acetylene. A combustible mixture of these gases is formed within

the blowpipes, the proportions of the combustible mixtures being adjusted by regulating valves 18. From the forward end of each blowpipe, as in

Fig. 2, the combustible mixture passes through a tube 19 to the upper end of a header 20. From

the lower end of each header, the combustible mixture passes through a tube 21 to head H or H'. Tubes 19 and 21 are provided with unions

22 and 23, respectively, so that heads H and H' may be adjusted to any desired position.

Heads H and H' are preferably secured in positioning device D at a workbench or any other convenient place, headers 20 being moved to the necessary positions when the heads H and H' are secured thereto, after which unions 22 and

45 23 are tightened.

The quenching medium supply means Q includes a manifold 24 having at one end an inlet

25 through which a cooling medium, such as water, is supplied. Leading from the side of

50 the manifold are a pair of tubes 26, which conduct the cooling medium to heads H and H'. Tubes 26 are preferably relatively flexible, so

that each tube may easily be connected to head H or H' irrespective of the position in which

55 the heads are placed. Leading from the end of the manifold, opposite inlet 25, is a vertical pipe

27 provided with a valve 28. The upper end of

60 vertical pipe 27 is provided with a packing gland

29 which surrounds an overflow pipe 30, which

may be moved upwardly and downwardly to any

desired vertical position. The pressure of water

65 through inlet 25 is preferably adjusted so

that a small amount of water flows continuously

from the open upper end of pipe 30. When the

pressure of the cooling medium in manifold 24

exceeds a predetermined value, excess cooling

medium will flow out of the open upper end of

overflow pipe 30. Thus, the pressure of cooling

medium supplied to heads H and H' will remain

essentially constant, and the pressure of cooling

medium supplied to each head will be the same.

In addition, if the flow of water through the

open upper end of pipe 30 ceases, this will indicate a lack of sufficient pressure, and serves as

75 a warning to the operator that the heads may

become overheated, or the heated surface portions may be insufficiently quenched. If it is not desired to use overflow pipe 30 to regulate the pressure of cooling medium, valve 28 may be closed.

The positioning device D, as in Figs. 1-3, includes a pair of arms 31 and 32 which are pivotal about a common center. Arms 31 and 32 are symmetrical, i. e., they are similar in shape but reversed in configuration, and the upper end of each arm is formed as a relatively narrow cylindrical segment 33 or 34. Cylindrical segments 33 and 34 are interfitting and have equal radii, the arms being pivotal about a stud 35 which extends rearwardly from the center of cylindrical segment 34 and passes through an aperture in a leveling plate 36 and thence through an aperture in the center of cylindrical segment 33. Arms 31 and 32, which are thus pivotal about the centers of cylindrical segments 33 and 34 as a common center, may be secured in any desired radial position with respect to each other and/or plate 36 by tightening a wing nut 37 on stud 35. The lower ends of arms 31 and 32 are provided with wide, deep slots 38 and 39 in which heads H and H' may be secured by clamping plates 40 pressed against the heads by wing bolts 41.

In order that any given set-up may be duplicated readily, the positioning device D, and preferably also heads H and H', are provided with means for indicating the radial positions of arms 31 and 32 and the longitudinal position of heads H and H' relative to the arms. In addition, at the upper end of plate 36 is a leveling surface 42, with a U notch 43 formed centrally thereof and extending down to the periphery of cylindrical segments 33 and 34. In the bottom of notch 43 is an indicating mark 44 which cooperates with scales 45 and 46 in setting arms 31 and 32 in any predetermined radial position about their common center. Scales 45 and 46 are preferably graduated in degrees and may be stamped or etched around the periphery of cylindrical segments 33 and 34, respectively, or stamped on metal strips which are affixed to the periphery of the cylindrical segments by rivets. Scale 45 is stamped on, or affixed to, the periphery of cylindrical segment 33, and scale 46 is stamped on, or affixed to cylindrical segment 34, but reads in the opposite direction from scale 45. Consequently, arms 31 and 32 may be placed in identical positions about their common center, or at identical angles with respect to leveling surface 42, or a perpendicular thereto, merely by aligning identical marks on scales 45 and 46 with indicating mark 44. For instance, as illustrated in Fig. 2, each arm is set at an angle of 50° with respect to leveling surface 42, or at an angle of 40° with respect to a perpendicular to the leveling surface.

Each arm 31 or 32 is also provided with an indicating mark 47 adjoining slot 38 or 39, each mark being spaced the same distance from the edge of the arm. To cooperate with mark 47, a suitable scale 48, preferably reading in inches or increments thereof, is stamped or etched on each head, as in Fig. 3. Merely by aligning identical marks on each scale 48 with indicating marks 47, heads H and H' may be placed in exactly corresponding positions in slots 38 and 39.

Any particular setting of the blowpipe heads H and H', or other heads adapted to be used in connection with the positioning device, may be easily and quickly repeated once the correct

position has been determined for any particular gear tooth. Assuming that the angular setting of arms 31 and 32 and the proper position of heads H and H' in slots 38 and 39 are known, the positioning device and the heads are taken to a workbench or other suitable place, where they may be assembled easily and quickly. After the proper marks on scales 45 and 46, indicating the same number of degrees, are aligned with indicating mark 44, arms 31 and 32 are clamped in the proper radial position by tightening wing nut 37. Then heads H and H' are secured in slots 38 and 39 by tightening wing bolts 41, the same distance mark on each scale 48 being aligned with indicating mark 47. The assembled positioning device and heads are then taken to the work set-up and the heads H and H' connected to unions 23, blowpipes B and B' having been placed in parallel relationship by proper adjustment of vertical arm 12 and slides 14 and 16. Before unions 22 and 23 or clamps 15 and 17 are tightened, a level is placed on surface 42 and heads 20 or blowpipes B and B' twisted so that surface 42 is exactly level. This will place the center of stud 35 and indicating mark 44 in vertical alignment. In addition, blowpipe B or B' may be moved forwardly or backwardly in clamp 15 or 17, as necessary, so that each head will be the same distance from arm 10, which is positioned at right angles to the center line of a shaft 49, upon which gear G is mounted, and consequently also at right angles to the center line of tooth T. Clamps 15 and 17 and unions 22 and 23 may then be tightened, and tubes 26 attached to the heads.

The gear G is supported so that the center line of tooth T is vertical, and the entire assembly of support, blowpipes, heads and positioning device are then moved laterally, if necessary, by moving laterally adjustable slide 4, so that the centers of stud 35 and indicating mark 44 are in exact vertical alignment with the center line of tooth T. (This is relatively easily done, for the center line of shaft 49 is also in vertical alignment with the center line of tooth T.) Then the entire assembly, if necessary, is raised or lowered by adjusting the vertical position of slide 7, so that surface 42, for instance, is the proper distance above the top of tooth T. The heads H and H' will thereby be positioned accurately.

The positions of heads H and H' may readily be changed for treatment of a different gear tooth merely by adjusting the positioning device and the heads clamped therein to positions in which the proper marks on scales 45, 46, and 48 coincide with indicating marks 44 and 47. In repositioning the heads, it is normally unnecessary to change the position of slides 14 and 16 or loosen clamps 17, since a slight rotation of headers 20 will take care of any difference in the distance between the heads for a different tooth. The only other adjustment which probably will be necessary will be a vertical adjustment of the entire assembly to place surface 42 the proper distance above the top of tooth T. In connection with the use of the positioning device of this invention, it is desirable to provide tables indicating the proper angular setting of arms 31 and 32 and the proper setting of heads H and H' in slots 38 and 39, as well as the proper distance of surface 42 above the top of the tooth, for each size and type of tooth to be treated.

The positioning device D of Figs. 1 to 3 may remain attached to the heads H and H', since

the teeth being treated are relatively small and the heat to which the positioning device is exposed will normally not be sufficient to damage the same. However, if desired, a cooling medium may be circulated through the positioning device, particularly through the lower ends of arms 31 and 32. As shown in Figs. 19 and 20, arms 31' and 32' are hollow but otherwise similar to arms 31 and 32 of Figs. 1 to 3, so that a suitable cooling medium may be circulated therethrough from inlets 100 to outlets 101.

The positioning device D' of Figs. 4-7 is similar to the positioning device D just described, but includes means for adjusting the relative height of the positioning device and heads with respect to the top of a gear tooth and rotatable clamps at the lower end of the pivoted arms by which other types of heads may be accurately positioned. Thus, the positioning device D' includes a pair of symmetrical arms 51 and 52 which are pivotal about a common center and the upper ends of which are formed as cylindrical segments 33' and 34' having equal radii. As before, the cylindrical segments interfit and are provided with scales 45' and 46' which read in opposite directions and which may be stamped or etched on the peripheries of the cylindrical segments, or stamped on metal strips riveted to the arms. Scales 45' and 46' cooperate with an indicating mark 44' on the side of a plate 53 provided with an upper leveling surface 42'. Arms 51 and 52 are pivotal about a stud 54 extending outwardly from plate 53 and passing centrally through cylindrical segments 33' and 34', plate 53 being disposed outside the cylindrical segments, rather than between them, in order to accommodate the means for positioning the device the proper distance above the top of the tooth and in vertical alignment with the center line of the tooth, which will be described later. As before, arms 51 and 52 may be clamped in any desired radial position by a wing nut 37'.

The lower ends of arms 51 and 52 are formed as cylindrical segments 55 and 56, respectively. Cylindrical clamping blocks 57 and 58, each having radii equal to those of cylindrical segments 55 and 56, are rotatably secured to the lower ends of arms 51 and 52, and may be clamped in any desired radial position by tightening wing nuts 59 on studs 60, the latter of which extend from the center of each clamping block and centrally through a suitable hole in cylindrical segments 55 or 56. Each clamping block is provided with a scale 61, preferably reading in degrees and stamped around the periphery of the block, which cooperates with a suitable indicating mark 62 on cylindrical segment 55 or 56 (see Fig. 5). Scales 61 read in opposite directions, while scales 61 and indicating marks 62 are placed in exactly corresponding positions on blocks 57 and 58 and cylindrical segments 55 and 56, respectively.

Each clamping block is provided with a wide, deep slot 63, in which heating heads H and H' of Fig. 4, or heads H'' and H''' of Figs. 5 and 6, may be secured by clamping plates 40' pressed against the heads by set screws 64. When a different type of head, such as heads H'' and H''' of Figs. 5 and 6, is used in hardening a large gear tooth T', each clamping block is rotated through 180° and attached to the upper end of the head. As in Figs. 17 and 18, head H—to which head H' is similar but asymmetric—comprises an elongated body having a longi-

tudinal heating passage 105 and cooling fluid passage 106 parallel thereto. The combustible mixture is supplied through inlet connection 21, while the cooling fluid is supplied through an inlet connection 108, to which tube 26 of Figs. 1-3 is connected.

Heads H'' and H''' are similar to those disclosed in the aforementioned Roger O. Day application Serial No. 169,373, now U. S. Patent No. 2,224,006. Head H'' is illustrated in greater detail in Figs. 21-23, head H''' being similar but asymmetric to head H''. Head H'' is provided with a surface 115 which is inclined to the sides of the head and forms one surface of a lower portion 116, which forms a lower end of reduced thickness and permits the head to be inserted between two closely spaced gear teeth. The head H'' is also provided with an inlet 117 to which the combustible mixture conduit 21' may be connected, and passages 118 and 119 which lead the combustible mixture to a distributing chamber 120 in the lower end of the head. A plurality of heating gas outlets 121 of substantially equal diameter lead from the chamber 120, terminating in the surface 115, and are preferably disposed in staggered relation in substantially vertically rows, so that the heating jets produced will tend to overlap and produce a more even heating effect. In addition, the distance between centers of adjoining outlets 121 increases progressively from the lower to the upper end of each row. Outlets 121 are spaced progressively further apart upwardly from the lower end of each row, so that closely adjoining heating jets will apply a greater amount of heat adjacent the root of the tooth and a progressively lesser amount upwardly towards the top of the tooth.

The passage 119 may be disposed substantially perpendicularly to the chamber 120, so that the combustible mixture will not be projected directly into the upper of the outlets 121, and a uniform distribution of the combustible mixture to all of the outlets 121 will be obtained. The passage 118 may be drilled from the upper end of the head and the passage 119 from the surface 115, the ends of the passages being closed by suitable means, such as plugs 122 which are secured in the ends of the passages in a suitable manner, such as by welding or brazing. The distributing chamber 120 may be formed by a suitable slot in the lower portion of the head, the outer periphery of the slot being closed by a substantially U-shaped strip 123 secured to the head in a suitable manner, such as by welding or brazing.

The head H'' is also provided with an inlet 125, to which the cooling and quenching fluid conduit 26 may be connected and from which an inclined passage 126 leads downwardly through the head to a distributing chamber 127, disposed alongside of and substantially parallel to the combustible mixture distributing chamber 120. A plurality of quenching fluid outlets 128 lead from the distributing chamber 127, terminating in the inclined surface 115 of the head, and are preferably inclined rearwardly and away from the heating gas outlets, desirably at an angle of about 30°, so that the quenching jets will not interfere with the heating flames. The quenching outlets 128 are also disposed in a plurality of rows so as to obtain complete quenching without splashing and interference with the heating flames. Inasmuch as the quenching outlets are inclined at an angle to the direction

in which the cooling and quenching fluid is discharged from the passage 126 into the chamber 127, it is unnecessary to provide a supplementary directing passage similar to the heating gas passage 119. The passage 126 and chamber 127 may be drilled from the top of the head and lower portion 116, and the open ends thereof closed by suitable means, such as plugs 129 which are secured therein in a suitable manner, such as by welding or brazing.

Indicating marks 65, as in Fig. 4, are placed in corresponding positions on clamping blocks 57 and 58 alongside slots 63, to cooperate with scales 48 on heads H and H', respectively, so that the heads may be positioned properly in slots 63. Heads H'' and H''' may be provided with scales similarly stamped or etched thereon, or provided with indicating marks 66, as shown. Heads H'' and H''' are of a type normally used in treating only one size of gear tooth, i. e. 1 D.P. (diametral pitch), 1½ D.P., 2 D.P., 3 D.P., or 4 D.P., while heads H and H' are of a type adapted to treat either 5 or 6 D.P. Thus, heads H'' and H''' will normally require only a single setting, and a single indicating mark will suffice for such setting. Also, in many instances, a single indicating mark will suffice on heads H and H', when positioned by device D'.

A groove 67 is formed in the front of plate 53, as in Fig. 7, in which a bar 68 is slideable perpendicularly to surface 42'. The upper end of bar 68 is slotted, and a stud 69, extending forwardly from plate 53 or formed as an extension of stud 54, extends forwardly through the slot in bar 68. Bar 68 may be clamped in any desired position by tightening a wing nut 70 on stud 69. The lower end of bar 68 is provided with a fork 71, and an indicating mark 72 on bar 68 cooperates with a scale 73, etched or stamped on plate 53 along one side of groove 67, to permit bar 68 to be placed in the correct position in groove 67, as in Fig. 7.

Heads H and H', or heads H'' and H''', are clamped in the correct longitudinal position in clamping blocks 57 and 58, and arms 51 and 52 are clamped in the correct radial position, at a workbench or other suitable place, as previously described for positioning device D. In addition, bar 68 is clamped in the correct position by aligning indicating mark 72 with the correct mark on scale 73.

After the positioning device D' and heads have been assembled, the heads are connected to headers 20, surface 42' leveled, tubes 26 connected to the heads, and unions 22 and 23 and clamps 15 and 17 tightened, as previously described. With surface 42' level, the axis of the two heads will be in a vertical position parallel to the axis of tooth T or T'. Unless already in the correct position, the common center of arms 51 and 52 is placed directly above the center line of tooth T and the heads placed in correct position with respect to the sides of the tooth, by adjusting the horizontal and vertical slides which are the normal complements of the carriage or traversing mechanism previously referred to. By such adjustments, the entire assembly, including the blowpipe support, is moved upwardly or downwardly, and laterally to either side, as the case may be, until fork 71 engages the top edges of the tooth, as in Fig. 6. Since surface 42' is level or horizontal, and bar 68 is perpendicular thereto or vertical, when the arms of fork 71 engage the top edges of the tooth, the common center of arms 51 and 52 will be disposed directly above the center line of the tooth and

the heads will be correctly positioned with respect to the tooth, all automatically. When relatively small teeth are being treated, the positioning device D' may remain affixed to the heads, except bar 68 is moved upwardly to the position of Fig. 4, to prevent damage to the same. When larger teeth are being treated, as in Fig. 6, the positioning device D' is preferably removed. If desired, and as previously pointed out, a cooling medium may be circulated through the positioning device D', particularly through clamping blocks 57 and 58 and the lower ends of arms 51 and 52, and the device left clamped to the heads during hardening.

Further in accordance with this invention, apparatus may be constructed by which the blowpipe heads are movable universally in a plane, and supplied with a combustible mixture of gases from a single blowpipe and with a cooling medium from a single source. As illustrated in Figs. 8 to 16, such apparatus may include a manifold 75, having a combustible mixture inlet 76 at the rear end thereof, to which a nipple 77 attached to the forward end of a blowpipe B is secured. The combustible mixture is led from inlet 76 into a passage 78 extending transversely of the manifold, and thence to outlets 79 at either end of passage 78 and drilled from the front of the manifold. The manifold is also provided with a transverse cooling fluid passage 80, to one end of which a valve 81 is connected and to the opposite end of which a pressure gauge 82 is connected. A suitable cooling fluid, such as water, is supplied by a hose 83 to valve 81, which controls the flow of cooling fluid to passage 80, gauge 82 being utilized in adjusting the pressure of the cooling fluid. Disposed centrally of passage 80, and drilled in the front of the manifold, are a pair of cooling fluid outlets 84.

The apparatus also includes a pair of headers 85, which are substantially identical in construction. As in Figs. 14 to 16, each header is provided with a combustible mixture inlet 86 at the upper end thereof leading to a central passage 87, and a cooling fluid inlet 88, in alignment with and disposed on the opposite side of the header from the combustible mixture inlet and leading to a cross passage 89. From each end of cross passage 89, a pair of longitudinal passages 90, parallel to central passage 87, carry the cooling fluid down through the header. From the lower end of each longitudinal passage 90, a pair of transverse passages 91 lead the cooling fluid to each end of a cross passage 92, while a cooling fluid outlet 93 connects centrally with cross passage 92. Also at the lower end of each header, and disposed opposite to but in alignment with cooling fluid outlet 93, is a combustible mixture outlet 94, disposed between cooling fluid passages 91 and connecting with the lower end of central passage 87. In addition, combustible mixture outlet 94 is on the opposite side of the header from combustible mixture inlet 86, and, similarly, cooling fluid outlet 93 is on the opposite side of the header from cooling fluid inlet 88.

A pair of nipples and a union 95 connect the combustible mixture inlet 86 at the upper end of each header with one of the combustible mixture outlets 79 in the manifold, while a tube 96, bent around as in Figs. 8 and 9, connects cooling fluid inlet 88 in each header with one of the cooling fluid outlets 84 in the manifold. Secured in the combustible mixture outlet 94 at the lower end of each header is a suitable nipple connecting with a union 23' to lead the com-

burnable mixture to each heating head through a tube 21", and tubes 26', bent around as shown, convey the cooling fluid to each head from cooling fluid outlets 93 at the lower end of each header 85. The nipples attaching unions 23" and 95 to the manifold 75 and/or headers 85 may be secured in the respective combustible mixture inlets and outlets of the manifold or headers in any suitable manner, such as by welding or silver soldering, while nipples connecting suitable unions provided at the ends of tubes 26' and 96 may similarly be secured in the respective cooling fluid inlets and outlets of the manifold and headers. Tubes 21" and 26' are connected to the respective combustible mixture and cooling fluid inlets of heads H and H', or heads H" and H'", in the same manner as the connecting tubes previously referred to.

Since the respective inlets and outlets in the headers are disposed directly opposite each other, each header 85 may be moved through substantially a complete circle, i. e. about the inlets at the upper ends thereof. Consequently, the upper ends of the heating heads may be placed in any position about this circle. Furthermore, the tubes 26' also may be rotated through almost a complete circle, so that the heads themselves may be rotated about the combustible mixture tubes 21' as an axis. Thus, the heating heads are adjustable to any position in a plane, and therefore are substantially universally adjustable. As will be evident, positioning device D or D' may be utilized in conjunction with the manifold, headers, etc. of Figs. 8-16.

It will be apparent from the foregoing description that apparatus constructed in accordance with this invention not only includes a positioning device by which any particular predetermined position of a pair of blowpipe heads may be obtained with speed and accuracy, but also provides means whereby a uniform and constant flow and pressure of the cooling fluid of the heads can be obtained, as well as means whereby the heads may be made universally adjustable in a plane. It will be understood that other blowpipe heads than those described may be used, that types of connections differing from those described may be used, and that various changes in the apparatus may be made without departing from the spirit and scope of this invention, as defined in the appended claims.

What is claimed is:

1. A device for positioning a pair of separately supported blowpipe heads for hardening gear teeth or the like, comprising a pair of arms pivotal about a common center; means for indicating the angular position of each arm about said common center comprising a scale on each arm indicating the number of degrees of rotation of each arm with respect to said common center, one scale reading from a lower to a higher number of degrees in the opposite direction from which the other scale reads; and means for removably securing one of said heads to each arm.

2. A device for positioning a pair of blowpipe heads for hardening gear teeth or the like, comprising a pair of arms pivotal about a common center; means for removably securing one of said heads to each arm; and a fork for engaging the top of a gear tooth, said fork being movable toward and away from said gear tooth and being adapted to be secured in a relatively fixed position so as to space said device the proper distance from the top of said gear tooth,

3. A device for positioning a pair of blowpipe heads as defined in claim 2, said device including means for indicating the relative position of said fork with respect to said device.

5 4. A removable device for positioning a pair of blowpipe heads, comprising a pair of arms pivotal about a common center; a plate provided with a level indicating surface; means for indicating the angular position of each arm about 10 said common center; and means for removably securing one of said heads to each arm, said device being so constructed and arranged that said common center may be disposed above the center of a gear tooth having its top surface disposed substantially horizontally, and said level indicating surface may be positioned substantially horizontally and substantially parallel to the top surface of said gear tooth, whereby each head will be positioned accurately in operative relation with respect to one of the opposite sides of said gear tooth.

20 5. A device for positioning a pair of blowpipe heads for hardening a gear tooth having its top surface disposed substantially horizontally, as defined in claim 4, in which the upper end of each arm is shaped to form a cylindrical segment, and also in which said indicating means comprises a mark on said leveling plate and a scale on each cylindrical segment indicating the 30 number of degrees of rotation of each arm with respect to said indicating mark, one scale reading from a lower to a higher number of degrees in an opposite direction from which the other scale reads.

35 6. Apparatus for heat treating gear teeth or the like comprising a pair of blowpipe heads; means for supporting said blowpipe heads; and a separate device for positioning said heads, each in operative relationship with respect to one of the opposite wearing surfaces of a gear tooth, said device comprising a pair of arms pivotal about a common center, means adjacent one end of each arm for indicating the angular position of said arm about said common center, and 40 means for removably securing one of said heads to each arm, said means comprising a radially adjustable clamp pivotally secured to the other end of each arm.

50 7. Apparatus for heat treating gear teeth or the like as defined in claim 6, in which said device includes means for indicating the radial position of each clamp relative to the respective arm to which it is secured.

55 8. Apparatus for heat treating gear teeth or the like as defined in claim 6, in which said heads are adapted to be secured by said clamps in various positions longitudinally of said heads, and in which said device includes means for indicating the longitudinal position of each head with respect to the clamp by which it is secured.

60 9. Apparatus for heat treating a gear tooth or the like having an upper surface normally disposed substantially horizontally, comprising a pair of blowpipe heads; means for supporting said blowpipe heads; and a separate device for positioning said heads, each in operative relationship with respect to one of the opposite wearing surfaces of a gear tooth, said device comprising a pair of arms pivotal about a common center, means for indicating the angular position of each arm about said common center, level indicating means having an upper surface adapted to be positioned substantially horizontally and substantially parallel to the top surface of said tooth, 70 a fork movable upwardly and downwardly for

positioning said device in vertical alignment with the center line of gear tooth, and means for removably securing one of said blowpipe heads to each arm.

10. Apparatus for hardening the oppositely disposed wearing surfaces of a gear tooth or the like comprising a pair of blowpipe heads, each adapted to direct at least one high temperature heating flame and a cooling medium against successive portions of one of the opposite surfaces of said gear tooth; means for supplying a combustible mixture of gases; means for supplying a cooling medium; a manifold having combustible mixture and cooling medium inlets connected with the respective supply means, and passages leading to two combustible mixture outlets and two cooling medium outlets; a pair of headers, each having at its upper end combustible mixture and cooling medium inlets and at its lower end combustible mixture and cooling medium outlets, said headers also having passages leading from the combustible mixture and cooling medium inlets to the respective outlets, said inlets and outlets being disposed substantially in alignment on opposite sides of said headers at the upper and lower ends thereof; means connecting one of the combustible mixture outlets in said manifold

5 with the combustible mixture inlet at the upper end of each header; means connecting one of the cooling medium outlets in said manifold with the cooling medium inlet in the upper end of each header; and means for conducting the combustible mixture and cooling medium from the outlets in one header to one blowpipe head and from the outlets in the other header to the other blowpipe head.

10 11. Apparatus as defined in claim 10, including two headers, in each of which the combustible mixture inlet is disposed on the opposite side of the header from the combustible mixture outlet and the cooling medium outlet is disposed on the opposite side of said header from the cooling medium inlet.

15 12. Apparatus for hardening oppositely disposed surfaces of gear teeth or the like, comprising, in combination, apparatus as defined in claim 10; and a device for positioning said blowpipe heads, said positioning device comprising a pair of arms pivotal about a common center, means for indicating the angular position of each arm about said common center, and means for removably securing one of said heads to each arm.

CERTIFICATE OF CORRECTION.

Patent No. 2,322,305.

June 22, 1943.

FRANK McGUIRE, JR.

It is hereby certified that error appears in the printed specification of the above numbered patent requiring correction as follows: Page 1, second column, line 33, for "inoperative" read --operative--; page 7, first column, line 2, claim 9, before the word "gear" insert --said--; and that the said Letters Patent should be read with this correction therein that the same may conform to the record of the case in the Patent Office.

Signed and sealed this 27th day of July, A. D. 1943.

Henry Van Arsdale,
(Seal) Acting Commissioner of Patents.
